CLAIM

The ornamental design for a dental flosser, as shown and described.

DESCRIPTION

FIG. 1 is a side perspective view of a dental flosser showing my new design;

FIG. 2 is a top plan view thereof, a single finger grip shown for convenience of illustration;

FIG. 3 is a top, side perspective view thereof;

FIG. 4 is a bottom plan view thereof;

FIG. 5 is a side elevational view thereof, the other side being a mirror image;

FIG. 6 is a cross-sectional view thereof, taken on line A—A of FIG. 5;

FIG. 7 is a bottom, side perspective view of a second embodiment thereof, the other side being a mirror image, a single finger grip shown for convenience of illustration;

FIG. 8 is a side elevational view thereof, the other side being a mirror image;

FIG. 9 is a top, side perspective view of a third embodiment thereof, a single finger grip shown for convenience of illustration, the third embodiment is identical to the first except for the texture on the stem; and

FIG. 10 is a side elevational view thereof.

FIG. 1

FIG. 2

FIG. 3

FIG. 4

FIG. 9

FIG. 10
